UNITED STATES PATENT OFFICE.

ROY F. CARTER AND RICHARD W. ZIERLEIN, OF ST. LOUIS, MISSOURI.

CARBURETER.

SPECIFICATION forming part of Letters Patent No. 669,157, dated March 5, 1901.

Application filed October 27, 1900. Serial No. 34,571. (No model.)

To all whom it may concern:

Be it known that we, ROY F. CARTER and RICHARD W. ZIERLEIN, citizens of the United States, residing at St. Louis, State of Missouri, have invented certain new and useful Improvements in Carbureters, of which the following is a full, clear, and exact description, reference being had to the accompanying drawings, forming a part hereof.

Our invention has relation to improvements in carbureters or apparatus for manufacturing illuminating-gas; and it consists in the novel arrangement and combination of parts more fully set forth in the specification and pointed out in the claims.

In the drawings, Figure 1 is a vertical middle section of the tank and operating parts, a portion being shown in elevation. Fig. 2 is a horizontal section on line 22 of Fig. 1. Fig. 3 is a detail showing the manner of mounting the floats to the float-pipe. Fig. 4 is a sectional detail on line 44 of Fig. 1, showing the cock in an open position for the free passage of a siphon-tube intended to be inserted into the equalizer-pipe; and Fig. 5 is a diagrammatic view showing the manner of coupling the device to the supply-barrel.

The present apparatus is an improvement on the carbureter described in United States Letters Patent granted to us under date of May 15, 1900, and numbered 649,435, the object in the present case being to qualify the construction therein set forth, with a view of simplifying the same and insuring better and more uniform results and with a further view of enabling the operator to fill the generator or tank while the process of carbureting is going on.

In detail the invention may be described as follows:

Referring to the drawings, 1 represents a closed tank or generator having at the bottom thereof an air-chamber 2, with which communicates an air-supply pipe 3, leading to an air-pump. (Not shown.) Projecting from the center of the bottom of the generator is a guide-tube 4, open at both ends, the lower end being in communication with the air-chamber 2. Passed loosely about the guide-tube 4 is a float-pipe 5, closed at the top and open at the bottom, said pipe 5 being slightly longer than the guide-tube 4. Depending

from the peripheral walls of the float-pipe, adjacent the closed top thereof, are tubes 6, located diametrically opposite one another, 55 the said tubes having radially-deflected perforated extensions 6', each terminating in perforated semicircular discharge-pipes 7, reinforced by the parallel perforated cross-pipes 8 9, respectively. The pipe 5 is kept floated 60 in the hydrocarbon liquid in the tank (said liquid being any volatile hydrocarbon capable of generating gas) by the hollow cylindrical floats or tubes 10, secured to the pipe 5 and adjustable along the same by means of 65 a set-screw 11, passed through the vertically-elongated slot 12 of a strip 13, secured tangentially to the walls of the floats, the screw being carried by the interiorly-screw-threaded bosses 14, carried by the float-pipe and disposed diametrically at right angles to the deflected portions 6' of the tubes 6.

Leading from the air-chamber 2 and projecting through the roof of the tank is an equalizer-pipe 15, provided with an ordinary 75 faucet valve or cock 16, well known on the market. Leading from the pipe 15, above the tank, is a shunt or branch pipe 17 terminating in a faucet valve or cock 18, the end of the pipe being adapted to be coupled to a 80 hose leading to the bung-hole of a supply-barrel 19, in which the hydrocarbon is stored. Leading from the roof of the tank is a filling-tube 20, adapted to be coupled by a hose to the discharge-hole of the barrel, this arrangement rendering it possible to feed the tank while the process of carbureting is going on—that is to say, while the air from the air-pump is forced into the tank. By thus coupling the barrel to the pipes 17 20, as indicated, the 85 pressure in the pipe 17 forces the liquid in the barrel against any accumulated gas-pressure in the tank 1. Leading from the base of the filling-tube is the gas-delivery pipe 21, which leads to any source of consumption. 95

When it is desired to drain the chamber 2 of any waters of condensation which may have accumulated therein in course of time, the cock 16 is opened, Fig. 4, and a siphon-tube inserted through the valve and into the 100 pipe 15 down to the bottom of the said chamber 2, the waters of condensation being siphoned off in the well-known manner. In fact, the air-chamber 2 serves to condense

the greater portion of the moisture carried by the air-currents, which would otherwise be conducted into the tank and injuriously affect the illuminating qualities of the gas evolved 5 from the hydrocarbon in the tank.

The float-pipe 5 is additionally guided in its movements by the upper guide-pipe 22, projecting from the roof of the tank and closed at the top by a cap 23. The upper end 10 of the float-pipe is provided with a chain 24, whose lower end is secured to the said pipe and whose upper end is secured to the wall of the guide-pipe 22. This chain enables the operator to shake the float occasionally and 15 disengage any foreign matter and air-bubbles which may tend to clog the free passages of the perforations in the discharge-pipes 6' 7 8 9. Of course the chain is of sufficient length to permit the float-pipe to oscillate within the 20 limits made necessary by the variable depth of the liquid within the tank.

In order to better diffuse the hydrocarbon to the action of the air-currents, we provide the walls of the tank with a felt or other absorbent lining L, which by capillary attraction causes a portion of the liquid to be diffused in a sheet about the walls of the tank, and thereby become more susceptible to the disintegrating and evaporating action of the 30 air admitted into the tank. Like in our patent referred to, the object of making the floats 10 adjustable along the float-pipe is to control and adjust the depth or degree of submergence of the perforated pipes 6' 7 8 9 below the surface of the liquid, the adjustment 35 depending, of course, on the specific gravity of the hydrocarbon operated on. The arrows in Fig. 1 indicate the course of the air-currents and that of the gas evolved from the 40 liquid in the tank.

Having described our invention, what we claim is—

1. In a carbureter, a closed tank or generator, an air-chamber below the same, a pressure-equalizer pipe having its lower end communicating with the air-chamber, an air-supply pipe communicating with said air-chamber and with the interior of the tank, a filling-tube leading to the tank, the upper ends of the 45 50 equalizer-pipe and filling-tube being adapted to be respectively connected above and below

the surface of the liquid of a suitable supply-barrel, a gas-delivery pipe leading from a point above the liquid in the tank, a guide-tube leading from the air-chamber into the 55 tank, a float-pipe playing loosely over the guide-tube, a float for said pipe, and depending tubes leading from the upper end of the float-pipe to a point below the surface of the liquid, the lower ends of said tubes being open 60 to discharge air into the liquid, substantially as set forth.

2. In a carbureter, a closed tank or generator, an air-chamber below the same, an air-supply pipe leading to the air-chamber, a 65 pressure-equalizer pipe leading from the air-chamber to a point above the tank, a shunt or branch pipe leading from the equalizer-pipe, a filling-tube leading from the top of the tank, a gas-delivery pipe coupled to the 70 base of the filling-tube, cocks at the upper ends of the equalizer-pipe and branch pipe, a guide-tube leading from the air-chamber into the tank, a float-pipe playing loosely over the 75 guide-tube, a float for said pipe, depending tubes leading from the upper end of the float-pipe to a point below the surface of the liquid, perforated air-discharge pipes connected to the lower ends of the depending tubes, an exterior guide-pipe for the float-pipe projecting 80 from the roof of the tank, and suitable floats adjustable along the float-pipe, and a supply-barrel adapted to be coupled to the filling-tube and branch pipe aforesaid, the parts operating substantially as and for the purpose set forth.

3. In a carbureter, a tank or generator, a float-pipe located therein, screw-threaded bosses carried by the peripheral walls of the pipe, hollow floats or tubes, strips secured tangentially to the walls of the floats, elongated slots formed in the strips, and binding-screws passed through the slots and into the bosses, whereby the floats can be vertically adjusted along the float-pipe substantially as set forth. 95

In testimony whereof we affix our signatures in presence of two witnesses.
